UNITED STATES PATENT OFFICE.

WILLIAM JAMES, OF BROOKLYN, NEW YORK.

CARBURETER THROTTLE-VALVE.

1,097,977.

Specification of Letters Patent. Patented May 26, 1914.

Application filed April 22, 1913. Serial No. 762,858.

To all whom it may concern:

Be it known that I, WILLIAM JAMES, a citizen of the United States, residing in Brooklyn, in the county of Kings and State of New York, have invented certain new and useful Improvements in Carbureter Throttle-Valves, of which the following is a specification.

My present invention relates to an improvement in carbureters, and more especially to the intake or outlet valve for controlling the influx and amount of gas mixture that may be supplied to explosive gas engines. A great variety of such valves have been used, such as butterfly valves and the like, and I have found in practice that the form now to be described has many advantageous features over the types now in use.

Further, valves of the type disclosed in the accompanying drawings herewith have also been used but have been made entirely in the form of a casting and my improvement primarily consists in modifying the structure in such a manner as to make it more practical and economical in manufacture.

In the accompanying drawings, Figure 1 shows a conventional type of carbureter having a portion of the gas outlet end broken away. Fig. 2 is one form of my device removed from the carbureter. Fig. 3 is a plan view of one of the shutter members. Fig. 4 is a plan view of a co-acting shutter member. Fig. 5 is a plan view of the valve housing with the valve or shutter members removed. Fig. 6 is a sectional view of the same taken on the line 5—5, Fig. 5. Fig. 7 is a plan view of another form of shutter member. Fig. 8 is a sectional view of a modified shutter construction. And, Fig. 9 is a sectional view of a like type of shutter of the present type of construction.

In carbureters of the type shown in Fig. 1, under suction impulse of the gas engine piston, air is drawn in at the inlet opening 1, in the direction of the arrow 1', and, after passing down through the interior of the carbureter, comes forth from the outlet valve 2 in the direction of the arrow 2' mixed or saturated with the proper amount of explosive gas or gasolene vapor. This explosive mixture is led thence to the cylinder of the engine for explosion. For the purpose of controlling the supply of gas to the said cylinder and for throttling the speed of the engine or shutting it down entirely, I have

provided pinched between the said outlet pipe 2 and the body of the carbureter 3, and connecting and controlling the flow of explosive mixture through the same, a shutter valve which is comprised of a cast metal casing 4 and a pair of stamped sheet metal shutters 5 and 6. This valve is designed to be used with carbureters now in common use, to be located adjacent thereto in the line applying the engine with explosive mixture, to replace the costly and bulky valves now used and to economize space where so to do is highly desirable, and to that end its attaching means are made to match those most common in such apparatus. To these ends the valve casing 4 is provided with lugs 7 and 8 and therein bolt holes 9 and 10 which match corresponding bolt holes on the carbureter and, generally, on the suction valve which (Fig. 1) is illustrated as set upon the valve casing 4, and, by its finished flange, confining the shutters 5 and 6. Usually studs extend from the carbureter through bolt holes in lugs on the suction valve and in such cases the bolt holes 9 and 10 of the casing 4 will merely center it in the pipe line and it will be pinched between the carbureter and the suction valve.

In order to provide sufficient aggregate clear opening through the shutters 5 and 6 the casing 4 is made a squat bowl or truncated cone, with an orifice in its small end 15, to match that in the carbureter, a rabbet 16, in its face 22 for the shutters, and to insure good fits and smooth flow of explosive mixture its interior and faces are machined. A slot 18 in the rabbet 16 provides for angularly fixing the fixed shutter 6, and for the play of the arm 24 of the movable shutter 5. To one side of said recess 18 I provide a radially extending lug 11, tapped for a limit screw 12, provided with a set nut 13, and adapted to limit the motion of or position the movable shutter 5, to regulate the area of opening through the shutters. Both shutters 5 and 6 have sector-like matching openings 23 and central bores 20 and 21, for a pivot, 19, which connects them. The movable shutter 5 has a radial arm 24 terminating in a pin hole for connection with the engine or governor, whereby to operate the valve; and a depending lug to coact with the limit screw 12, for adjusting the flow. The fixed shutter 6 has a projecting segment, 17, to fix it in the casing with which it is preferably a forcing fit. To set the valve,

its bolt holes 9, 10, are slipped over the studs (not illustrated) of the carbureter which centers its inlet with the outlet thereof and the succeeding member in the pipe line (generally the suction valve) likewise set and bolted up with its flange against the face 22, thereby confining the shutters 5 and 6. The arm 24 of the movable shutter 5 is then suitably connected and the limit screw 12 adjusted.

It has heretofore been the custom in this type of valve to make the casting portion include, as an integral portion of the casting, the shutter portion shown as a separate member 6, and it is obvious that when the inner surfaces 14, 15 and 16 had to be machined and the apertures 23 in the shutter 6 had to be opened up, difficulties were encountered owing to the impracticable construction thereof. By providing the shutter member 6 as a separate element the same can be blanked out by punch press operation to an exact size, and thereafter forced into the machined casting as previously described.

There is shown in Fig. 9 a sectional view of a cast casing, as above described, the indices indicating the same component parts as shown in Fig. 1. Owing to the extra coring necessary in casting this piece, and the necessity of machining the interior thereafter, as well as facing and smoothing up the apertured valve portion thereof, it will be seen that this piece made as above described, is expensive. By my improved construction, however, the casting needs no core to cast its own interior, being self coring, but is more conveniently reached from the valve side for machining, whereas in the integral cast construction the interior must be machined from the rear, which is difficult and expensive.

Another form embodying my improved valve construction is shown in Figs. 7 and 8 wherein the fixed shutter member 6' is substantially of the same outline as the casting member 4, and the movable shutter 5' is of discoid form having an operating arm 24' thereon similar to arm 24 on member 5, Fig. 3. In this construction the movable shutter 5' is placed in the seat and the stamped sheet metal shutter member 6' is placed over the same and the assembled unit placed between the carbureter 3 and the outlet pipe 2, to be thereafter locked in position by means of the previously mentioned bolts. This is a modification of the sheet metal shutter construction previously disclosed and is analogous to the same, and permits of the same economy in manufacture.

Having thus described my invention, I claim:

1. A regulating shutter-valve adapted to

be interposed and registered in the pipe line between a carbureter and an engine and comprising a hollow, truncated cone provided with an opening in its small end adapted to register with the carbureter outlet and a slotted rabbet in its large end adapted to fix one and rockably mount the other shutter of a shutter valve; a perforated stamped-metal shutter fixed in said rabbet, and rockably mounted therein a perforated, stamped metal shutter; and means to fix said valve, in register, in said pipe line.

2. A regulating shutter valve adapted to be interposed and registered in the pipe line between a carbureter and an engine and comprising a hollow, truncated cone provided with an opening in its small end adapted to register with the carbureter outlet and a slotted rabbet in its large end adapted to fix one and rockably mount the other shutter of a shutter valve; a perforated stamped-metal shutter fixed in said rabbet, and rockably mounted therein a perforated, stamped metal shutter; a radial operating arm thereon; and means to fix said valve, in register, in said pipe line.

3. A regulating shutter valve adapted to be interposed and registered in the pipe line between a carbureter and an engine and comprising a hollow, truncated cone provided with an opening in its small end adapted to register with the carbureter outlet; a slotted rabbet in its large end adapted to fix one and rockably mount the other shutter of a shutter valve; a radial lug adjacent to said rabbet and a limit-screw therein; a perforated stamped-metal shutter fixed in said rabbet, and rockably mounted therein a perforated, stamped metal shutter; a radial operating arm thereon and means on said arm to engage said limit screw; and means to fix said valve, in register, in said pipe line.

4. A regulating shutter valve adapted to be interposed and registered in the pipe line between a carbureter and an engine and comprising a hollow, truncated cast cone with its faces and interior machined and provided with an opening in its small end adapted to register with the carbureter outlet and a slotted rabbet in its large end adapted to fix one and rockably mount the other shutter of a shutter valve; a perforated stamped-metal shutter fixed in said rabbet, and rockably mounted therein a perforated, stamped metal shutter; and means to fix said valve, in register, in said pipe line.

WILLIAM JAMES.
